US0D1027961S

(12) **United States Design Patent** (10) **Patent No.:** **US D1,027,961 S**
(45) **Date of Patent:** **** May 21, 2024**

(54) **CASE FOR ELECTRONIC DEVICE**

(71) Applicant: **SHENZHEN GUANGYIPENG TECHNOLOGY CO., LTD.**, Shenzhe (CN)

(72) Inventor: **Jie Weng**, Shenzhen (CN)

(73) Assignee: **SHENZHEN GUANGYIPENG TECHNOLOGY CO., LTD.**, Shenzhen (CN)

(**) Term: **15 Years**

(21) Appl. No.: **29/822,097**

(22) Filed: **Jan. 5, 2022**

(51) LOC (14) Cl. **14-03**

(52) U.S. Cl.

USPC **D14/250**

(57) **CLAIM**

The ornamental design for a case for electronic device, as shown and described.

DESCRIPTION

FIG. 1 is a perspective view of a case for electronic device showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the case for electronic device where the case for electronic device is in a first configuration of use;

FIG. 10 is a perspective view of the case for electronic device where the case for electronic device is in a second configuration of use;

FIG. 11 is a perspective view of the case for electronic device shown with environmental subject matter (a pen) in an exploded view;

FIG. 12 is another perspective view of the case for electronic device shown with environmental subject matter (a pen) in an exploded view; and,

FIG. 13 is a perspective view of the case for electronic device shown with environmental subject matter (a foldable mobile phone) received in the case.

Broken lines depict portions of the case for electronic device that from no part of the claimed design; Additional broken lines in FIGS. 11 and 12 showing a pen and in FIG. 13 showing a foldable mobile phone, illustrate environmental subject matter and form no part of the claimed design.

1 Claim, 13 Drawing Sheets
